J. H. N. CHRISTIAN,
WATER HEATING ATTACHMENT FOR STOVES,
APPLICATION FILED MAY 8, 1919.

1,316,940.

Patented Sept. 23, 1919.

John H. N. Christian

By William G. Linton

Attorney

UNITED STATES PATENT OFFICE.

JOHN H. N. CHRISTIAN, OF MONTREAL, QUEBEC, CANADA.

WATER-HEATING ATTACHMENT FOR STOVES.

1,316,940.

Specification of Letters Patent. Patented Sept. 23, 1919.

Application filed May 8, 1919. Serial No. 295,617.

To all whom it may concern:

Be it known that I, JOHN H. N. CHRISTIAN, a subject of the King of Great Britain, residing at Montreal, Province of Quebec, 5 Canada, have invented certain new and useful Improvements in Water-Heating Attachments for Stoves; and I do hereby declare that the following is a full, clear, and exact description of the invention, such as will 10 enable others skilled in the art to which it appertains to make and use the same.

The present invention relates to water heating attachments for gas stoves and more particularly pertains to the detachable type 15 of devices, wherein the heating element is designed to present a maximum surface to the direct flame of the burner, while allowing for the perfect combustion of the gases.

The principal object of the invention is 20 to provide a greater heating area for the water coil and means for detachably supporting the same within the stove.

A further object of the invention is to provide a heating element, which may be 25 adjusted to present a maximum surface to the flame of the burner.

With the above and other objects in view which will hereinafter appear as the description continues, the invention consists of 30 the novel features of construction, combination and formation of parts as will be hereinafter fully described and particularly pointed out in the appended claims.

In the accompanying drawings has been 35 shown a simple and preferred form of the invention, it being, however, understood that no limitation is necessarily made to the precise structural details herein exhibited, but the right is hereby reserved to any 40 changes, alterations or modifications to which recourse may be had that come within the scope of the claims without departing from the spirit of the invention or sacrificing the efficiency of the same.

45 In the accompanying drawings:

Figure 1 is a perspective view of my improved device;

Fig 2 is a sectional elevation of a gas range illustrating the application of my device thereto;

Fig. 3 is a cross section of a portion of the front wall of the range and a coupling nut, illustrating the attachment of one of the coil ends to the range;

Fig. 4 is a plan view of the coil unit, with the range plate in section;

Fig. 5 is a sectional elevation of the coil unit on line 4—4 of Fig. 4; and

Fig. 6 is an elevational view of one of the strap elements.

Referring now more particularly to the accompanying drawings wherein like and corresponding parts are designated by similar reference characters throughout the several views.

The well known type of water heaters, comprise devices which are operable independently of the gas range, having their own burners and regulating valves. In the present invention, the heating unit 1, comprises continuous coils preferably formed of copper tubing and having an inlet tube 2 and the outlet tube 3.

The gas range designated by the numeral 4 is of the usual construction, having upper 75 and lower ovens 5 and 6 and a heating space 7 disposed therebetween. A burner 8 is mounted immediately above the lower oven 6 and its upper portions extend within the heating space 7. The burner 8 has a connection 9 extending through an opening in the front wall 10 of the range 4 and said connection carries the pilot 11.

The front wall 10, above the pilot 11, is likewise provided with two openings 85 adapted for reception of the ends of the inlet and outlet tubes 2 and 3, which latter are exteriorly screw threaded at 12 and carry collars 13. The threaded ends of the inlet and outlet tubes 2 and 3 are passed 90 through the front wall openings and the interiorly threaded nipples 14 are screwed upon the threaded ends and when tightened, serve to draw the said ends outwardly to bind the collars 13, against the inner surface 95 of the front wall 10, of the range. In this manner the heating coil unit is supported in a horizontal plane and disposed centrally of the heating space 7.

The nipples 14 are provided with exterior 100 screw threads 15, to afford proper connection with pipes leading from the water supply and to the boiler respectively.

As has been heretofore stated, the heating unit comprises a plurality of continuous coils of tubing and to present a maximum surface to the flame of the burner, I provide means for adjusting the coils to position the same, entirely over the heating space 7, so that a greater heating radius 110 is afforded. To accomplish the above function I spread apart the coils and for hold-

ing the latter in adjusted or spread position, I employ the strap member 16, composed of two elements 17 and 18, having registering slots 19, through which passes 5 a bolt 20 carrying a nut 21. The outer ends of the strap elements 17 and 18 are bent over at 22 and embrace the outer coils as illustrated in Fig. 6, and when the nut 21 is adjusted upon bolt 20, the strap elements 10 are held together and prevent the movement of the said coils, contractive or otherwise. A similar strap member 22 has its ends bent over at 23 to embrace the ends of the inlet and outlet tubes 2 and 3 contiguous to the collars 13 and hold the said tubes at this point.

It will thus be seen that the coil tubes when adjusted in the manner stated, will be disposed in staggered relation one with the 20 other, as illustrated in Fig. 5, and will present their greatest area to the direct flame of the burner, while allowing for the perfect combustion of the gases.

The device may be readily removed from 25 the range, by unscrewing the nipples 14, likewise adjustment of the coils may be accomplished in the same manner.

In the use of my improved heating device a continuous supply of hot water is 30 maintained and the use of a separate heating plant for the heating of water is obviated.

Having thus fully described my invention, what I claim as new and desire to set 35 cure by Letters Patent is:

1. A water heating attachment for gas stoves, comprising a coil element arranged for connection to a suitable water supply and outlet, said coil element adapted for

position within the heating space of the 40 range and disposed parallel with the burner, means for supporting said coils in position, and means for adjusting said coil element to present a maximum heating surface to the burner. 45

2. A water heating attachment for gas stoves comprising a coil having water inlet and outlet tubes, said tubes formed with collars and having their ends screw threaded, the said threaded ends adapted for projection through openings in the front wall of the stove, nipples arranged on the said ends, for drawing the said collars into engagement with the stove wall, for holding said coil in a horizontal plane with the 50 heating space of the stove, the said coil tubes being transversely adjustable to present a maximum heating surface to the flame of the stove burner. 55

3. A water heating attachment for gas 60 stoves comprising a coil having water inlet and outlet tubes, said tubes formed with collars and having their ends screw threaded, the said threaded ends adapted for projection through openings in the front wall 65 of the stove, nipples arranged on the said ends, for drawing the said collars into engagement with the stove wall, for holding said coil in a horizontal plane with the heating space of the stove, the said coil tubes 70 being transversely adjustable to present a maximum heating surface to the flame of the stove burner, and strap elements for holding said tubes in adjusted position. 75

In witness whereof I have hereunto set my hand.

JOHN H. N. CHRISTIAN.
